CLAIM

The ornamental design of an antenna housing, substantially as shown and described.

DESCRIPTION

FIG. 1 is a top perspective view of an antenna housing, showing my new design;

FIG. 2 is a bottom perspective view thereof;

FIG. 3 is a top plan view thereof;

FIG. 4 is a bottom plan view thereof;

FIG. 5 is a left elevational view thereof;

FIG. 6 is a right elevational view thereof;

FIG. 7 is a front elevational view thereof; and,

FIG. 8 is a rear elevational view thereof.

The broken line in the figure drawings represents unclaimed portion of the design only, which forms no part of the claim.

1 Claim, 8 Drawing Sheets(56)
